BOBBIN MARKING MECHANISM

Otto W. Schlums, Whitinsville, Mass., assignor to
 Whitin Machine Works, Whitinsville, Mass., a
 corporation of Massachusetts

Application December 30, 1941, Serial No. 424,945

15 Claims. (Cl. 242—1)

1

The invention relates to apparatus for marking the mass of yarn wound on bobbins or the like, such as are delivered from automatic textile winding and analogous machines, and consists of delivery mechanism incorporated in or applied to such machines operating to pass filled bobbins therefrom, as wound, and at the same time mark the yarn of each bobbin with an identifying mark or symbol. The marking refers to the character of the yarn so that in subsequent processes the mill operatives can observe what kind of yarn the bobbin carries without having to examine it closely, the marking pigment used being either fugitive or easily removable in the ultimate product or when this function has been served.

Such marking has heretofore been done by hand with colored chalk by the operator, and in the case of certain kinds of winding machines this has required special rehandling of the bobbins for no other purpose than to put the marks upon them, besides which the variety of markings available for use has been limited to the number of distinctive chalk colors.

By the present invention each bobbin is marked automatically as produced by imprinting directly on its mass of wound yarn a mark which may be a chalk mark if desired, and which may be distinctive not only as to color, but also as to form or combination, thereby affording a practically unlimited range of marking for the more reliable identification of the yarn. Within the term bobbin is included any other similar form of wound textile package, whether on a core or not, and the term pigment is used to refer to any marking substance of the kind indicated, whether liquid or solid.

According to this invention the bobbins are taken one by one while in process of emerging from the winding mechanisms of the machine and carried onward through a path defined by opposing driven surfaces which engage the bobbin with some pressure, and one at least of these surfaces is a marking device, or a marking roller, supplied with the marking pigment, and acting to transfer such pigment in a selected pattern to the yarn mass as it passes. The bobbin-engaging members are driven continuously so that they become active to mark and pass each bobbin onward instantly that it reaches contact with them, marking it at the same time.

The drawings hereof illustrate preferred embodiments of means within the invention for carrying out the action referred to, Fig. 1 being an end elevation of a known form of multiple-head automatic winding machine having the inven-

2

tion applied; Fig. 2 is a plan of the marking mechanism associated one with each winding head; Fig. 3 is an elevation of Fig. 2 from line III—III; Figs. 4 and 5 represent examples of marked bobbins; Fig. 6 is a plan for using liquid pigment; and Fig. 7 is an elevation of Fig. 6. Fig. 8 is a partial top plan of the winding machine.

The apparatus includes as its supporting means several bracket arms 1 bolted at intervals along the frame 2 of the winding machine, parts of which appear in Fig. 1, and as will be understood. The brackets carry a longitudinal supporting rod 3 running the length of the machine, and also the journal bearings for a longitudinal roller shaft 4 likewise running the length of the machine and driven by a train of reducing gearing, marked 5, in turn driven by the main or power shaft 6.

The longitudinal roller shaft 4 is driven continuously and in a position directly below the row of heads in which the bobbins are held while they are being wound (Fig. 1) and adjacent the outlets of the chutes 7 into which the filled bobbins drop on being released from the chucks in such heads. When the chucks separate or open a wound bobbin drops upon the upper slope of the chute on which it turns as it slides or falls so that it reaches the lower end of the chute butt first. At 7^b is a conventional chuck showing.

30 The bobbins are commonly retained, momentarily, in the chute while the yarn is being severed and are then released by the opening of the escape door 7^a. It will be understood that each winding head, of which there may be many in one machine, is self-contained and automatic, delivering its bobbin independently of the other heads as soon as it has been fully wound with yarn or thread.

40 Adjacent each such chute the shaft carries fast thereon a grooved or concave roller, such as 8, and associated with each such roller there is an opposed or complementary pressure member, preferably also in the form of a roller marked 9. Between them, these rollers define a continuation of the bobbin discharge path and into which the bobbin protrudes as it emerges, butt first, from the opened end of the chute. The pressure means or roller 9 is carried in a frame 10 swinging on the longitudinal shaft 3

45 as an axis and spring-urged toward the grooved driven roller 8 by spring 12. In the intervals between marking operations, this frame rests against a fixed stop 11, which is an arm also carried on the support rod 3, and desirably so 50 adjustably set on that rod that the rollers are

normally spaced widely enough apart to allow the butt of a bobbin to enter between them, with or without exerting pressure upon it, but in any event closely enough together to grip and make a firm contact with the yarn mass upon such bobbin. Within the range of an ordinary automatic winder various styles and sizes of bobbins may be delivered by the chute at different times and the normal spacing between the driving roller and its pressure means including the spring 12, is designed as indicated to provide a suitable pressure on the yarn for each of them, and so that when entry occurs the rotation of the driven roller 8 passes the bobbin slowly onward toward the place of deposit. Since the butt diameter is often as large or larger than the yarn mass diameter, the entry into the pass between rollers which are set to press on the yarn is apt to be uncertain and result in the blocking of the chute and possible injury to the winding mechanism. This is avoided by providing ribs or cleats 8^a on the driving rollers of proper form to interlock with or catch hold of the ridges or rings on the bobbin butt thus to draw the bobbin into the pass under all circumstances. The stop arms 11 will be understood to be initially set in the adjusted positions referred to, and being all set-screwed to the support rod 3 the passes through all of the rollers can be simultaneously and conveniently changed when required by 30 rocking such rod in its supporting brackets.

In Figs. 1 to 4 the pressure means or roller 9 is a marking roller, rotated by the bobbin, and is shown as made in twin form, with two adjacent rims or treads, the equivalent of two rollers mounted side by side. Each tread is supplied with pigment, which in this case is a solid such as chalk, and applied thereto by a pencil of that material loosely held in a feed tube 14 through the open bottom of which the pencil bears upon the tread surface or surfaces of the roller as the latter rotates. These tubes are supported side by side in a bracket 15 also carried on the swinging roller frame 10 so as to preserve a constant relation to the roller; they may be supplied with spring followers or other means for pressing the chalk downwards when necessary.

The rotation of the marking roller by the bobbin causes its tread surface to rub the end of the chalk pencil so as to grind off some of the chalk in the form of powder which clings to the tread surface, such surface being appropriately roughened as by cementing emery flour to it. Although this chalk powder adheres to the rough tread, enough of it is taken off by the yarn mass under the rolling contact with the latter to produce a distinct marking. In the form illustrated, two continuous chalk stripes are thus imprinted on the yarn, the treads of the roller being continuous. This makes a novel and conspicuous identification for bobbins. The roughening of the treads can also be discontinuous, if desired, one or both, in such case making interrupted or broken stripe marks, and of course any combination of such markings, in the same or different colors, and as suggested by Figs. 4 and 5. The twin rolling means 9 is mounted for ready removal from its frame, as by unscrewing the thumb-nut 16, so that other markers can be substituted to make more or fewer marks on the yarn. While the invention contemplates supplying pigment to the roller 9 in any desired manner, its application in the form of a pencil of a solid substance like chalk

and in the manner described is preferred. In such case the marking pigment is prepared for transfer, that is to say, reduced to powder, by the actuation of the bobbin itself, to which the transfer is made, and since the transfer roller rotates only while engaged with the bobbin no more chalk is ground off of the pencils than is actually required for making the marks. It may be noted also that the adjustment of the springs 12 combines with the action of the cleats 8^a to provide the traction necessary for driving the transfer roller under the friction load imposed by the pencil or pencils. Instead of cleats the driving rollers could be provided with rubber surfaces which would be the equivalent.

Figs. 6 and 7 indicate the appropriate changes for using a liquid marking pigment and in the case where the lower or driven rollers, here marked 20 serve as the marking means. Each such roller is supplied with the pigment liquid by means of one or more relatively narrow transfer discs, such as 21, which bear against it and have their lower edges dipping into the liquid held in a container 22. Two such discs are shown transferring two lines of pigment to the surface of driven roller 20 and each has its own pigment supply which can be of different colors, each disc being journaled in its own removable container which is adjustable on its support, as indicated at 23, so as to cause it to produce the appropriate contact with the roller 20. This constitutes the equivalent of the chalking means of the other form. The bobbin passing over the roller picks up the pigment and is marked accordingly. Thereafter the continuing rotation of the roller 20, in the intervals between markings, insures that it will be properly supplied with pigment for its next action. As in the other form the marking roller may also present either continuous or interrupted surfaces to contact by the yarn thus to produce such patterns as are indicated in the drawings.

The pressure means 24 in this case is a roller as before, which is carried in a similar spring-pressed frame 10 normally held against the stop 11 so that the yarn mass can be gripped under the pressure appropriate for advancing it and transferring the pigment from the drive roller to it as the bobbin passes along. The construction affords the advantage that the pressure-rolling-means such as 24 can also be a pigment-transferring means, if desired, like the roller 9 with either single or plural treads, thereby marking both sides of the bobbin at once so that it can be identified from any angle from which viewed. In both forms the chutes constitute means for entering the bobbins into the action of the marking mechanism and such action is under way while the bobbin is still partly in the control of the chute as can be observed in the drawings. From the rollers the marked bobbins fall into a receiving box, not shown.

I claim:

1. As an adjunct to a bobbin-winder comprising a row of automatic and independently-operating bobbin-winding heads provided with delivery chutes which receive and discharge bobbins in the sequence in which they become fully wound by said heads, the combination of a longitudinal bobbin-drive shaft, mounted on said machine parallel to the row and common to all the winding heads thereof, a series of bobbin-drive rollers distributed along and driven by such shaft, each roller respectively adjacent to a delivery chute of a winding head, and each having a pressure

means cooperating with it to advance a bobbin, means for continuously driving such shaft to continue the delivery of bobbins as soon as presented by said chutes, and means for applying a marking pigment to the bobbins while engaged by said rollers.

2. As an adjunct to a textile winding machine comprising a plurality of automatic and independently-operating bobbin-winding heads having bobbin-discharge chutes receiving bobbins in the sequence in which wound, the combination of a series of bobbin-drive rollers located respectively closely adjacent to each of said chutes to engage the forward ends of bobbins while still within the chutes, means for continuously driving said rollers, and means for transferring marking pigment to the yarn masses on the bobbins while engaged by said rollers.

3. As an adjunct to a bobbin-winding machine comprising a plurality of automatic, independently-operating bobbin-winding heads having bobbin-discharge chutes which receive bobbins in the sequence in which wound, the combination of a series of bobbin-drive rollers located respectively closely adjacent to each of said chutes, a series of cooperating pressure rollers for said drive-rollers adapting them to engage the forward ends of bobbins while still within such chutes, means for continuously driving said rollers, means for supplying marking pigment to the rollers of one of said series, and means for holding said pressure rollers in positions in which they are spaced from the drive-rollers by a distance greater than the diameter of the bobbin butts, whereby pigment is transferred only to the yarn masses on the bobbins.

4. As an adjunct to a bobbin-winding machine comprising a plurality of automatic independently-operating bobbin-winding heads having bobbin-discharge chutes which receive bobbins in the sequence in which wound, the combination of a series of bobbin-drive rollers located respectively closely adjacent to each of said chutes, a series of cooperating pressure rollers for said drive-rollers adapting them to grasp bobbins, means for supplying marking pigment to one of said series of rollers, and means for holding said pressure rollers in positions in which they are spaced from the drive-rollers by a distance greater than the diameter of the bobbin butts, whereby pigment is transferred from the rollers only to the yarn masses on the bobbins passing therethrough.

5. As an adjunct to bobbin-winders comprising a row of automatic independently-operating bobbin-winding heads, the combination of a bobbin-drive shaft mounted longitudinally on such machine, a series of bobbin-drive rollers driven by such shaft with one roller appurtenant to each winding head, means for continuously driving said rollers, a series of normally non-rotary pressure rollers for cooperation respectively with said drive rollers and adapted to be rotated only by contact with the bobbins engaged between rollers, and means for supplying marking pigment to said normally non-rotary rollers for transfer therefrom to the yarn masses on the bobbins.

6. As an adjunct to a textile winding machine comprising a plurality of automatic independently-operating bobbin-winding heads having bobbin-discharge chutes which receive bobbins in the sequence in which wound, the combination of a series of bobbin-drive rollers located respectively closely adjacent to each of said chutes, a series of cooperating pressure rollers for said drive-rollers adapting them to grasp discharging bob-

bins and means for supplying marking pigment to the rollers of one of said series comprising more than one pigment holder for each of said rollers, whereby more than one mark is transferred from such rollers to the yarn on the bobbins.

7. As an adjunct to automatic apparatus for winding bobbins comprising a row of automatic independently-operating bobbin-winding heads, the combination of a bobbin-drive shaft mounted longitudinally on such machine, a series of bobbin-drive rollers driven by such shaft with one roller appurtenant to each winding head, a series of pressure rollers for cooperation respectively with said drive rollers adapting the latter to grasp and advance bobbins entering between them, and a corresponding series of pigment holders each adapted to hold solid pigment in rubbing contact with a roller of one of said series thereby transferring pigment from the rollers to the yarn masses on the bobbins.

8. As an adjunct to apparatus for winding bobbins comprising a row of automatic independently-operating bobbin-winding heads, the combination of a longitudinal supporting rod and an adjacent longitudinal bobbin-drive shaft both mounted on such machine in parallel relation, bobbin-drive rollers driven by such shaft with one roller appurtenant to each winding head, frames on said rod mounted to swing thereon, toward and from the drive rollers and having marker rollers journaled in their free ends, each frame carrying a pigment holder for the swinging roller thereof, and means for yieldingly holding said frames and the marker rollers carried thereby in a predetermined spaced relation to their respective bobbin-drive rollers adapting them to receive a bobbin between them.

9. As an adjunct to apparatus for winding bobbins comprising a row of automatic independently-operating bobbin-winding heads, the combination of a supporting rod and a bobbin-drive shaft both mounted longitudinally on such machine and adjacent to each other, bobbin-drive rollers driven by such shaft with one roller appurtenant to each winding head, roller-carrying frames mounted to swing on said rod and spring-urged respectively toward said drive rollers, marker rollers journaled in said swinging frames, pigment holders on said frames for the marker rollers thereof, and stop brackets mounted on said rod to limit the approach of said pressure rollers toward said other rollers.

10. As an adjunct to bobbin winders comprising a row of automatically independently-operating bobbin-winding heads, the combination of a bobbin drive shaft and an adjacent supporting rod both mounted longitudinally on such machine, a series of bobbin-drive rollers driven by such shaft with one roller appurtenant to each winding head, frames mounted on said supporting rod carrying a series of pressure rollers for cooperation respectively with said drive rollers, adapting the latter to grasp and advance bobbins, a corresponding series of pigment holders each adapted to hold solid pigment in rubbing contact with said pressure rollers thereby transferring pigment to the yarn masses on the bobbins, and means for continuously rotating said bobbin-drive rollers.

11. As an adjunct to a bobbin-winding machine comprising a plurality of automatic independently-operating bobbin-winding heads having bobbin-discharge chutes which receive bobbins in the sequence in which wound, the combination of a series of bobbin-drive rollers located respec-

tively adjacent to each of said chutes, a series of cooperating and normally non-rotating pressure rollers for said drive-rollers assisting them to advance bobbins received from such chutes, and means for supplying marking pigment to said series of pressure rollers for transfer therefrom to the bobbins, comprising holders for solid pigment pencils adapted to hold such pencils in rubbing contact with said pressure rollers, whereby the action of the bobbin itself on said rollers effects the transfer of the rubbed-off pigment to the yarn mass thereon.

12. As an adjunct to a bobbin-winder comprising a row of automatic bobbin-winding heads each having a delivery chute, the combination of a longitudinal bobbin-drive shaft mounted on said machine parallel to the row and common to all the winding heads thereof, a series of bobbin-drive rollers distributed along and driven by such shaft, each roller respectively adjacent to a delivery chute of a winding head, a series of pressure rollers respectively cooperating with each of said drive rollers to define continuation delivery paths for bobbins from the chutes respectively appurtenant thereto, and means for supplying marking pigment to both series of rollers thereby transferring marks to both sides of the bobbins passing from the winder.

13. As an adjunct to bobbin-winders comprising independently - operating bobbin - winding heads, the combination of a series of bobbin-drive rollers, one such roller being appurtenant to each winding head, means for driving said rollers to deliver bobbins, a series of pressure rollers respectively cooperating each with one of said drive rollers, means for supplying marking pigment to the rollers of one of said series for transfer therefrom to the yarn masses on the bobbins, a series of stop arms for determining the normal spacing

5 of said pressure rollers, with respect to said drive rollers, and a supporting rod on which such arms are carried, said rod being movable for simultaneously changing the spacing of all of said pressure rollers.

14. A bobbin-winder comprising a row of automatic bobbin-winding heads provided with delivery chutes to receive and discharge bobbins, a longitudinal bobbin-drive shaft, mounted on said machine parallel to the row and common to all the winding heads thereof, a series of bobbin-drive rollers distributed along the row and driven by such shaft, each roller respectively being located 10 respectively adjacent to a delivery chute of a winding head, and each being adapted to propel the bobbins endwise, a pressure sustaining means opposed to and cooperating with each drive roller to enable it to propel bobbins, means for continuously driving such shaft, and means for applying a marking pigment to the bobbins while engaged by said drive rollers.

15. A bobbin-winder comprising a row of automatic bobbin-winding heads provided with delivery chutes to receive and discharge bobbins, a longitudinal bobbin-drive shaft, mounted on said machine parallel to the row and common to all the winding heads thereof, a series of bobbin-drive rollers distributed along the row and driven by such shaft, each roller respectively being located 15 respectively adjacent to a delivery chute of a winding head, and each being adapted to propel bobbins endwise, an idly mounted roller opposed to and cooperating with each drive roller to enable it to propel bobbins, means for continuously driving such shaft, and means for applying a marking pigment to the bobbins while engaged by said drive rollers.

OTTO W. SCHLUMS.
